STAPLING IMPLEMENT

Robert W. Jenny, Westerly, R. I., assignor to Bostitch, Inc., Stonington, Conn., a corporation of Rhode Island

Application April 5, 1954, Serial No. 420,942

9 Claims. (Cl. 1—49)

This invention relates to improvements in stapling implements and more particularly to a power-operated stapler for fastening together various articles and objects and tacking in place sheets of fiberboard and other materials.

One object of the invention is to provide an implement of the type indicated which may be held in one hand and applied to the work in various positionings while being operated by pneumatic or hydraulic pressure.

Another object of the improvement is to provide a machine of the type indicated which may be used for driving staples having legs of varying length in accordance with the requirements of the work without necessitating any adjustment in the mechanism of the device.

Another object is to provide a machine having means for preventing the staples from jamming and clogging the throat through which they are driven due to misalignment of a staple therein or distortion in the shape of the staple.

Another object is to provide a machine of the type indicated which is more convenient for loading with staples and generally more efficient in use for various purposes.

The present improvements are embodied in an implement described in the following specification which discloses a preferred form of construction of the machine, by way of example, as illustrated by the accompanying drawings. In the drawings:

Fig. 1 is a longitudinal sectional view of the implement shown with the essential elements of its mechanism in operative relationship and its magazine loaded with staples;

Fig. 2 is a fragmentary side elevational view of the same showing the staple-magazine open for loading and illustrating the closure-abutment or nosepiece at the front of the magazine in part-section to show the throat through which the staples are driven;

Fig. 3 is a transverse sectional view of the fore part of the machine taken on line 3—3 of Fig. 1;

Fig. 4 is a perspective view of the closure-abutment or nosepiece which cooperates with the end of the magazine to form the staple-throat;

Fig. 5 is a perspective view of the staple-driver adapted to reciprocate in the throat of the machine;

Fig. 6 is a perspective view of the forward end of the staple-core and the staple-rest carried thereby;

Fig. 7 is a greatly enlarged sectional plan view of the nosepiece or closure-abutment for the magazine showing the contour of the throat and illustrating a staple held therein prior to its being driven;

Fig. 8 is an enlarged vertical sectional view of the forward part of the staple-magazine showing the nosepiece or closure-abutment which cooperates with the open end thereof and illustrating a staple in place in the throat prior to driving it therethrough;

Fig. 9 is an enlarged perspective view of one form of staple adapted for use with the present machine;

Fig. 10 is an end view of the same indicating in dash-

2

lines the angular displacement of the legs of the staple;

Fig. 11 is an enlarged face view of the nosepiece or closure-abutment for the front of the magazine showing a modification in the formation of the staple-throat;

Fig. 12 is a vertical sectional view similar to Fig. 8 and illustrating the modified formation of the staple-throat; and

Fig. 13 is a transverse sectional plan view of the closure-abutment and the end of the magazine similar to Fig. 7 but showing the modification in the throat illustrated in Figs. 11 and 12.

As herein illustrated and described the mechanism of the present machine is generally of the same construction and arrangement as that disclosed in my prior pending application for United States Letters Patent, Serial No. 393,347, filed November 20, 1953, and issued as Patent No. 2,714,208, on August 2, 1955. This type of machine may be power driven by pneumatic or hydraulic pressure and manipulated in one hand for applying it to different types of work. For example, the present implement may be used as a tacker for fastening placards to a wall or other support and for fastening wallboard in place in the building arts. In other instances, it may be employed in various manufacturing arts for the construction of crates, plywood containers, for tacking screens to frames and for various and sundry other purposes too numerous to mention herein.

The present improvements are particularly directed to means for guiding the staples through the throat at the front of the magazine to prevent their movement being obstructed, for example by misalignment of the legs of the staple, to jam therein and clog the throat and render the machine inoperative until the obstruction is removed. Most staples produced today are of excellent manufacture, uniform in shape and properly dimensioned to fit machines of the present type. However, due to careless handling or rough treatment in shipping the staples in commercial packages they may become slightly distorted or malformed such as by having their opposite legs twisted or bent out of alignment. In certain instances even a perfectly formed staple may tend to rock or cant in the throat as it is being driven so that its legs are inclined rearwardly in such manner as to catch on an obstruction and prevent proper driving of the staple. Wire staples are conventionally assembled in multiple by attaching them together in strips or "sticks" of convenient length for packaging and for loading them in the magazine of a machine. When a staple is separated from the stick by the impact of the driver descending in the throat there is a tendency for it to rock or cant and incline its legs rearwardly so that their ends may strike the abutments projecting from the sides of the core to prevent the staple from sliding down in the throat. In a condition of this character the impact of the reciprocating driver against the head or crossbar of the staple will usually cause its legs to be bent or distorted so that its passage through the throat is obstructed to clog the machine; or otherwise it may be driven out from the throat in distorted shape. To prevent such contingencies causing binding of a staple in the throat and clogging of the machine, or its malformation when driven therefrom, the present invention provides means tending to rock or cant the staple about a definite axis so as to displace its legs forwardly in such manner as to clear the ends of the legs from any obstruction therebeneath. In other cases it provides that if the legs of the staple are displaced out of alignment they will yet have freedom of movement in the throat so as not to obstruct the passage of the staple therethrough.

Referring to the present drawings, the implement may comprise an upper hollow handle-member 2 containing a

valve-housing 3 communicating with the bore of a vertical cylinder 6 in which is a piston 4 connected to actuate the staple-driver 5. A horizontal magazine 10 for the staples is pivoted midway of its ends on a strut 11 depending from the handle-member 2 to adapt it to be swung about its pivotal axis as shown in Fig. 2 to open its forward end for loading staples thereinto.

At the forward end of the implement is a nosepiece 12 depending below the cylinder 6 and forming a fixed or stationary closure-abutment for the magazine 10 when the latter is in closed relationship as shown in Fig. 1. The nosepiece or closure-abutment 12 cooperates with the end of the magazine 10 to form a throat 15 through which the staples may be driven into the work. The throat 15 consists in a novel construction and arrangement of parallel grooves directly related to the present improvement as will be specifically described hereinafter. Suffice it to state that the staple-driver 5 is connected to the piston 4 and adapted to be power-operated to force it downwardly through the throat 15 to drive a staple 3 after severing it from the strip or stick in the magazine 10. A helical spring 16 located within the bore of the cylinder 6 with its lower end seated on a disk 7 at the bottom thereof acts to return the piston 4, and thereby the driver 5, to the upper end of the stroke after each staple-driving operation.

Air under pressure is admitted into the hollow handle-member 2 from a flexible hose 17 attached to its end to cause it to flow through a conduit 18 communicating with the valve-housing 3. The valve-housing 3 has a port 19 leading into the upper end of the bore of the cylinder 6 and the valve is preferably of the quick-opening poppet-type comprising a vertical plunger 20 carrying a head 21 which seats against the upper end of the housing to close the valve. A trigger 22 is pivoted below the handle-member 2 in engagement with the lower end of the plunger 20 for actuating the latter to open the valve, the construction and arrangement of these last described elements being substantially the same as in my prior pending application referred to above.

Referring to Figs. 1 and 3, the magazine 10 is constructed and arranged substantially as described in my prior application, being constituted by a hollow trough-shaped member formed of sheet-metal with a bottom 23 and upstanding sides 24. A staple-core 25 of U-shape in cross-section extends longitudinally between the sides of the magazine 10 and is arranged to slide forwardly therein when the magazine is opened (Fig. 2) as described in my prior application. The core 25 is slid forwardly under the tension of a spring 26 pocketed in a bore 27 in a block 28 fastened in the rearward end of the core surrounding and slidable on a pin 29. Forming an extension of the forward end of the core 25 is a staple-rest or guide 30 constructed as a solid metal block or member fastened between the sides of the core and slidable therewith in the magazine 10 for projecting it forwardly beyond the end thereof. A pin 32 (Fig. 1) projects upwardly from the bottom of the magazine 10 through a slot 33 in the core 25 to limit its forward sliding movement. The member 30 may have a crowned upper face 31 corresponding to the crown or crossbar of the staple 3 (Fig. 9) with its main portion extending downwardly to form a foot 35 which is adapted to rest against the work when the implement is applied thereto for setting the staples therein. Projecting rearwardly from the upper portion of the member 30 are vertical flanges 36 which may be welded or otherwise suitably fastened to the inner faces of the sides 37 of the core 25. The flanges 36 are recessed along their sides to form shoulders 38 abutting the forward edges of the sides of the core 25 and welded thereto in a close flush joint. By this formation, the upper portion of the staple-rest or member 30 is of a width corresponding to that of the core 25 so that the staples may be slid forwardly thereacross to deliver singly into the throat 15 for passage

therethrough. Below this upper portion of the rest or member 30 are shouldered abutments 40 and slightly therebelow the member is further widened by shouldered abutments 41 forming the foot 35. The front face of the member 30 is recessed with a vertical slot 42 bounded on its opposite sides by flat faces provided for an essential purpose later explained.

Referring to Figs. 1, 2 and 4, the nosepiece or closure-abutment 12 is of generally tapered form depending from a pair of arms 47 which are bolted at 46 to the under side of a horizontal plate-like member 48 fastened in the bottom of the cylinder 6. The plate-like member 48 is bored to receive the lower shouldered end of the cylinder 6 to fixedly mount it thereon with its main portion extending rearwardly and recessed at 49 to receive the ears 50 which project upwardly from the magazine 10. A cross-pin 51 extending through the ears 50, the end of the plate 48 and the lower end of the strut 11, suspends the magazine 10 from the main handle-portion 2 of the implement while adapting it to pivot about a central axis. This method of mounting the magazine on the implement provides that it may be rocked into the position shown in Fig. 2 for loading staples thereinto through its forward end while adapting it to be held rigidly with its open end closed by the nosepiece or abutment 12 as shown in Fig. 1.

A latch 55 slidably mounted in a slot 54 on the under side of the plate-member 48 has a tapered portion 56 engageable through the inclined slot 57 of a looped keeper 58 projecting upwardly from the magazine 10. The keeper 58 is L-shaped with a foot 59 welded or otherwise fastened to a U-shaped-sheet-metal member 60 extending longitudinally within the magazine 10 above the core 25 (Figs. 2 and 3). The member 60 serves as a cover overlying the core 25 for preventing the staples from riding up thereon. The sides of the members 60 underlie the inturned upper flanges on the sides 24 of the magazine 10. A helical spring 65 pocketed in a bore 61 in the latch 55 with its rearward end engaging the end of the slot 54 acts to slide the latch forwardly to engage it with the slot 57 in the keeper 58. A pair of pins 66 project from the sides of the latch 55 through slots in the sides of the member 48 with their ends held in serrated plates 67 overlying the sides of the member. The plates 67 provide finger-grips for sliding the latch 55 rearwardly to release its end from the keeper 58 whereby to permit the forward end of the magazine 10 to be swung downwardly for opening it. A flat leaf-spring 68 bears against the top of the forward portion of the latch 55 to frictionally hold it in released position. The forward end of the spring 68 is bent downwardly for engagement with the keeper 58 when the forward end of the magazine 10 is swung upwardly so as to release the frictional pressure of said spring and permit the latch 55 to be slid forwardly by its spring 65 for locking the magazine in closed relationship. During the closing of the magazine 10 in this manner, the forward portion of the staple-rest 30 will engage and slide along the rearward side faces of the nose or closure-abutment 12 to force the core 25 rearwardly into the magazine 10 so that eventually, as the magazine reaches its horizontal closed relationship, the staple-rest 30 will align with and abut the side of the nosepiece 12 for cooperation therewith in forming the staple-throat.

The staples 3 are usually supplied to the magazine 10 in stick form to slide in straddled relation along the core 25. A staple-pusher 70 of usual construction is mounted to slide along the core 25 for feeding the staples forwardly in the magazine 10. A helical spring 71 attached to the pusher 70 at one end extends forwardly around a roller 72 and then rearwardly with its other end fastened to the bottom of the core at 73 for urging the pusher forwardly. A hold-back or detent-pawl 75 is pivoted between the sides of the member 60 at its forward end for operation under the tension of a spring 76 to cause its rearward

pointed toe 77 to engage with the staples for preventing their escape through the open forward end of the magazine 10 when the latter is in open position. As shown in Fig. 2, the top of the staple-pusher 70 is formed with a series of notches 78 with which the toe 77 of the pawl 75 engages when the pusher is slid forwardly sufficiently to feed the last staple from the magazine.

Referring to Figs. 3 and 5, the staple-driver 5 is in the form of a relatively thin blade reinforced by ribs 80 tapering from its upper end down to its lower edge. The upper thickened neck portion 81 of the driver 5 is T-shaped with a head 82 held in a slot 83 in the side of the piston 4. Referring now to Figs. 3, 4, 7 and 8, the nosepiece or abutment 12 forming the closure for the forward end of the magazine 10 is of novel construction as regards the formation of the staple throat therein. The side of the nosepiece which faces the member 30 and abuts the end of the magazine 10 is formed with a relatively deep vertical recess 84 having an intermediate convexly faced rib 85 projecting forwardly therein and extending longitudinally thereof; this part of the throat in the nosepiece 12 having an important function for engaging the crowns or crossbars of the staples as they are driven down through the throat. At either side of the projecting rib 85 are tapering slots 86 for receiving the tapered ribs 80 on the driver-blade 5. With the tapered ribs 80 on the driver-blade slidably received in the slots 86 the laterally-projecting flange-like portions 87 of the driver-blade 5 will slide in the main slot 84 of the throat 15 at the sides of the projecting rib 85.

The present machine, like that of my prior pending application referred to above, is especially adapted for operating on staples having a crowned head or crossbar (Fig. 9) with its apex or peak at the center thereof. Staples of this type have certain advantages as set forth in United States Letters Patent No. 2,052,553 of September 1, 1936, the truss-like form of the crossbar or crown *c* tending to distribute the driving force applied thereto to properly set the staple in the work and further serving to stiffen and strengthen the whole staple. As another advantage, during the driving of the staple the force of the driver exerted against the apex or peak *a* of the crowned head or crossbar *c* tends to flatten the head and thereby urge the legs of the staple to spread outwardly away from each other. For this reason the legs are caused to be guided along the sides of the throat without any tendency for them to buckle or bend inwardly and therefore a well-formed stitch may be applied to the work.

The crowned head or crossbar *c* of the staple *s* also has an advantage in connection with its use in the present machine which provides means cooperating therewith for preventing the staple from canting or "tumbling," as it is sometimes called, and causing its legs to swing rearwardly to engage against shoulders or abutments at the sides of the staple-core. With the present form of construction the apex *a* (Fig. 9) at the center of the head or crossbar *c* of the staple *s* is caused to slide downwardly in a straight course along the convex face of the central rib 85 in the nosepiece 12. The rib 85 is thus adapted to act as a fulcrum about which the staple may be rocked slightly by the leverage of the member 30 engaging below the apex *a* of the head *c* as the core 25 is resiliently urged forward by the tension of the spring 26 (Fig. 1). As is usually provided the depth of the staple throat or recess 15 in the nose-piece 12 is slightly greater than the normal thickness of the wire in the staples to allow for variations in the diameter of the wire as sometimes occur. By this provision the spaces 92 at the sides of the rib 85 allow sufficient clearance to accommodate the slight tilting of the staples. It will be observed by reference to Fig. 7 that the two upper vertical faces 90 (Fig. 6) on the staple-rest or member 30 bear against the crossbar *c* of the staple at points outwardly beyond its central apex *a* and due to pressure of the member 30 thereagainst the tendency is to rock the staple about the fulcrum formed by the

rib 85 engaging the apex *a* of the crossbar *c*. Stated another way, the two faces 90 pressing against the outer lengths of the crossbar *c* tend to rock the staple on the rib 85 as a fulcrum due to their leverage on the crossbar *c* at points below the apex *a* which bears against the rib. In this way the legs of the staple have a tendency to swing forwardly at their lower ends, as indicated by dotted lines in Fig. 10, so that their ends will clear any obstruction at the rear of the throat during the first part of the descent of the staple through the throat or until they are guided by the widened lateral faces 91 on the foot 35 of the member 30. The purpose of the extra depth in the recess 84 of the throat 15 (Fig. 7) will now be apparent, the relatively shallow clearance space 92 at either side of the rib 85 allowing the lower ends of the legs of the staple to swing forwardly, if necessary, in the manner and for the purpose above explained.

The method of operation of the complete implement is explained as follows: To load the magazine 10 with staples its forward end is swung downwardly as shown in Fig. 2 after releasing its latch 55. The latch 55 is withdrawn from the keeper 58 by grasping the finger-pieces 67 to slide it rearwardly against the pressure of the spring 65; the latch being held in this retracted position by the frictional action of the spring 68 bearing against its forward upper face. As the latch 55 is released and the forward end of the magazine 10 swung downwardly by rocking it about the pivot-pin 51 the staple-core 25 will be slid forwardly by the spring 26 on pin 29 as shown in Fig. 2 to advance the staple-rest or member 30 beyond the end of the magazine. A refill or stick of staples *s* may then be entered into the magazine 10 by supporting its end on the rest 30 and pushing it rearwardly to retract the staple-pusher 70 against the tension of its spring 71.

The magazine may be closed by swinging its forward portion upwardly to latch it in position with the nose-piece 12 abutting its open end. As the end of the magazine swings upwardly the keeper 58 will strike against the downturned end of the spring 68 to release the pressure of the latter on the latch 55 so that the spring 65 will slide the latch forwardly to engage it with the keeper as shown in Fig. 1. As the forward portion of the magazine 10 is swung upwardly the staple-rest or member 30 slides along the forward face of the nosepiece or closure-abutment 12 to force the core 25 rearwardly in the magazine 10 and withdraw the member 30 into the position represented in Fig. 1. As the magazine 10 is closed the forward end of the detent-pawl 75 strikes against the disk 7 in the bottom of the cylinder 6 to rock the pawl and release its toe from the staples. The staples *s* are thus released to be fed forward by the advance of the pusher 70 for delivering the foremost staple into the throat 15 beneath the driver 5.

Referring now to Figs. 7 and 8, it will be observed that as the member 30 at the end of the core 25 is urged forwardly by the resilient pressure of the spring 26 on the core its faces 90 will engage against the crossbar *c* of the staple *s* at two points spaced outwardly from the apex *a* of the crown which bears against the projecting convex face of the rib 85 in the throat 15, see Fig. 7. This engagement which occurs as the staple being operated upon is driven down along the front of the rest 30 by the descent of the driver 5 applies a leverage to the staple due to the resilient pressure of the member 30 against its crossbar *c* at points outwardly beyond and below the central apex *a*, thereby tending to force the lower ends of the legs of the staple forwardly. It is obvious that only a slight tilting or rocking of the staple may be necessary to clear the lower ends of its legs from the abutments 40 on the sides of the member 30, the space 92 at either side of the rib 85 (Fig. 7) in the throat 15 providing a clearance for the lower ends of the legs to enter if the staple is canted in the manner explained above. The depth or width of the space 92 is somewhat exaggerated in Fig. 7 to more clearly illustrate the arrangement of the

parts for the method of operation explained above. After the staple being driven has passed the abutment 40 it will descend through the throat 15 without further difficulty and may be driven into the work without danger of being distorted in shape or becoming malformed during the driving operation.

Figs. 11, 12 and 13 illustrate a slightly modified form of construction of the grooves in the throat 15 of the nosepiece 12, it being observed that the space 92 between the end of the member 30 and the opposing face of the throat 15 is further recessed by deeper grooves 95 in the upper part of the throat. While this added clearance is usually unnecessary it may be provided as an added precaution so that should the staple be malformed with its legs bent out of alignment there would still be room for the canted leg to be received in the groove 95 in such manner as to adapt the other leg to escape striking the abutment 40 on the side of the core 25.

It will be apparent from the foregoing description that the present improvement in the construction of the implement and its method of functioning insures unhampered passage of the staples through the throat as they are driven by the descending driver so that staples of the present type may be effectually applied to the work in proper form to secure a more satisfactory stitch. It will be understood that the present machine will operate with equal advantage using staples of somewhat different shape from that herein illustrated, for example the head or crossbar of the staple may have an arched crown instead of being peaked at the center.

The present improvement provides for efficient operation of the implement for continuously driving and setting the staples in the work without danger of a staple becoming jammed in the throat to clog and prevent the operation of the machine. Moreover, the machine may be operated with staples of varying size without any adjustment of its mechanism.

While the improvement is herein shown and described as applied to a particular type of stapling implement, it will be understood that it is susceptible of other applications for different types of machines and variations may be made in the structure and arrangement of the mechanism thereof without departing from the scope of the invention as expressed in the appended claims. Therefore, without limiting myself in this respect, I claim:

1. In a stapling implement having a staple-driver for driving crowned staples into the work and a magazine for progressively feeding the staples to said driver, a member having a slot-like recess forming a throat through which the staples may be driven, said recess provided with a central vertical longitudinally-extending rib having a convex face projecting into said throat for engagement with the crossbar of a staple at the center of its crown, and resiliently-operated means for engaging said crossbar of the staple at points spaced laterally from its center and slightly below its apex whereby said means tends to cant the staple to displace its legs forwardly for preventing their ends from encountering any obstruction at the rear liable to impede the passage of the staple through the throat.

2. In a stapling machine having a staple-driver, a magazine for containing crowned staples, and means in the magazine for feeding the staples progressively beneath said staple-driver, a nosepiece at the front of the magazine having a recess forming a throat for receiving staples fed from the magazine, said recess having a central convexly-faced vertical rib projecting into said throat for engaging against the central highest point on the crowned crossbar of a staple, means slidably mounted at the end of the magazine and formed with portions adapted to engage the crossbar of the staple at points spaced laterally from and below the center of its crown, and resilient means for urging said member forwardly whereby its pressure against the staple tends to rock the latter to cant its legs forwardly.

3. In a stapling implement having a magazine for containing a supply of staples having crowned crossbars, a closure for the forward end of said magazine provided with a recessed throat for receiving staples fed from the magazine, and a driver reciprocable in said throat for driving the staples therethrough to apply them to the work, said closure for the magazine provided with a central rib extending vertically through its throat and projecting into said throat for engagement with the highest portion or peak of the crowned crossbar of a staple, means slidably mounted at the forward end of the magazine and having spaced apart faces adapted to engage the crossbar of said staple at points spaced laterally and downwardly from its peak, and resilient means for sliding said member to cause it to exert a thrust on the staple as the latter is driven tending to rock the staple about the rib as a fulcrum whereby its legs will be prevented from canting rearwardly to encounter an obstruction in passing through the throat.

4. In a stapling machine having a magazine open at its end, a core slidable longitudinally within the magazine and adapted to support a series of crowned staples straddled thereacross, a closure-abutment positioned opposite the open end of the magazine and formed with a recess providing a throat through which the staples may be driven, a reciprocatory driver for driving the staples through said throat, said recess in the closure-abutment formed with a rib extending vertically throughout its length centrally thereof and having a convex face projecting into said throat for engagement with the peak of the crowned head of a staple, means at the end of the slidable core for engaging said head of the crowned staple at points spaced laterally and downwardly from its central peak, and resilient means for sliding the core to cause its end to press against the ends of the head of the staple in a manner tending to rock its legs forwardly to prevent them from striking against any obstruction at the rear of the throat during the driving of said staple.

5. In a stapling machine, a supporting member having means therein for actuating a staple-driver, a magazine pivoted to said member to adapt it to be swung to expose its open end for receiving a supply of staples, a nosepiece on said supporting member adapted to overlie the open end of the magazine when the latter is swung upwardly into closed relationship, said nosepiece formed with a slot-like recess extending vertically to provide a staple-throat opposite end of the magazine, means for feeding crowned staples in the magazine to deliver them into said throat, said throat formed with a relatively narrow rib extending longitudinally thereof and projecting into the center of the throat for engaging with the central highest portion of the crowned head of a staple, a core in the magazine for supporting the staples in straddled relation thereon, a member slidably mounted at the front of the magazine, resilient means for sliding said member forwardly towards the recess in the nosepiece, and spaced means at the front of said slidable member adapted to engage the head of the staple at points spaced laterally from its center and downwardly from its peak to thereby tend to rock the staple and prevent its legs from being canted rearwardly as it is driven through the throat.

6. In a stapling implement, a main member carrying a reciprocable staple-driver and power means for actuating said driver, a magazine mounted on said member and provided with an opening at its end through which the staples may be loaded into the magazine, a core extending longitudinally within the magazine and slidably forwardly therein, means for feeding the crowned staples along the core to deliver them singly beneath the staple-driver, a closure-abutment cooperating with the magazine to close its open end, said abutment having a slotted recess forming a vertical throat through which the staples may be driven, said recess provided

with a central convex rib projecting into the throat for engagement with the crowned head of the staple at its highest point, a staple-rest at the forward end of said staple-core formed with a depending foot and having a relatively shallow recess in its forward portion forming opposite spaced faces adapted to engage the crowned head of the staple at points spaced laterally outward and downward from its peak, and a spring for advancing the staple-rest towards the throat in the closure-abutment.

7. In a stapling implement comprising a handle-member mounting a reciprocable staple-driver and having power-means for actuating said driver, a staple-magazine pivotally mounted on said handle-member with its open end adapted to swing away therefrom for loading staples thereinto, a core extending longitudinally within said magazine and slidably forwardly therein, a spring for sliding said core in the magazine, a nosepiece depending from the handle-member and formed with a recess adapted to cooperate with the open end of the magazine to form a throat through which the staples may be driven, means in the magazine for feeding crowned staples along the core to deliver them into the throat beneath said driver, said recess in the nosepiece having a central convex rib extending longitudinally thereof and projecting into the center of the throat to adapt it to engage the peaked upper portion of the crown of a staple, and a member mounted at the forward end of the staple-core to slide therewith and provided with a shallow slot forming spaced-apart faces adapted to engage the crowned head of a staple at points spaced laterally outward and downward from its upper peak, said last-named member being resiliently urged against the crown of the staple in a manner tending to rock the latter on the rib as a fulcrum whereby to prevent the legs of the staple from being canted rearwardly.

8. In a stapling implement for applying staples having crowned heads, a staple-driver, a magazine for containing staples having crowned heads or crossbars, and means for feeding staples from the magazine to the driver,

said implement having a slot-like throat through which the staples may be driven, said throat dimensioned to provide a clearance at the front of a staple and having means projecting into the center of the throat for engaging the head of a staple at the highest point on its crowned head, and resiliently-operated means for engaging the head of said staple at points below the point of engagement of said projecting means therewith, said resiliently-operated means acting to apply pressure to the staple tending to cant it about a fulcrum at the high point on its head whereby to prevent the ends of the staple legs receding to encounter any obstruction at the rear liable to impede the passage of the staple through the throat.

9. In a stapling machine for operating on staples having crowned heads or crossbars, a magazine for holding a supply of said staples, a driver movable relatively to the magazine to drive the staples into the work, and means for feeding the staples from the magazine to said driver, the combination therewith of means at the end of said magazine forming a throat through which the staples may be driven, said throat having a relatively narrow longitudinal rib projecting into the throat from one side thereof with parallel slots at the sides of said rib, and resiliently-operated means on the opposite side of said throat having laterally-spaced projecting portions adapted to bear against the crown of the staple below that portion thereof engaged with the projecting rib in the throat to exert pressure tending to cant the staple for displacing its legs forwardly so as to prevent the ends of the legs from meeting any obstruction during the passage of the staple through the throat.
